UNITED STATES PATENT OFFICE.

ARTHUR RAYMOND DAVIAU, OF WATERVILLE, MAINE.

BIRD CAGE.

Application filed December 27, 1926. Serial No. 157,276.

The object of the invention is to provide a bird cage or similar article which may be built up of a plurality of tubular elements or straws, or similar devices, which may be obtained upon the market in standard 5 lengths,—the article including a body portion formed in a particular manner, and by the use of a particular method, a bottom with which the body is connected, and a top 10 and suspension device,—all as more fully disclosed below.

With the foregoing and other objects in view, the invention consists in the novel construction and arrangement of elements described, illustrated and claimed, it being understood that modifications may be made within the scope of the claims without departing from the spirit of the invention.

The invention also consists in the method 20 of assembling the device.

In the drawings forming part of this application,

Figure 1 is a view of the complete device or construction in elevation. 25 Figure 2 is a detail view partly in section and partly in elevation, showing an end portion of one of the elements, or straws, employed in the construction of the device, a particular joint being provided for.

The bottom 10 is surrounded by a wire ring 11, with which it has connection, and the elements forming the side walls of the cage are connected with the ring, and project below the latter in order to provide the 30 structure illustrated in the lower portion of Figure 1. An upper metallic ring 12 is of substantially the size of the ring 11, and constitutes an upper element for the body portion of the cage. Between these rings I secure a series of elements or straws 13, constituting an outer series, and another set or 35 series forming an inner group.

These elements 13 and 14, that is the two series which they represent, are relatively 40 positioned as shown in Figure 1, that is the straws of one series are at an angle with those of the other. Two elements 13 and 14 are first connected at a given point, as shown at 12', being secured to ring 12, so that a 45 plurality of pairs are provided, spaced at suitable intervals, and these elements 13 and 14 of each pair may be assumed to be suspended from ring 12 during the process of manufacture, the next step being to secure 50 the elements of one series to the lower ring 11, which is connected with the bottom 10.

At this stage there is one series of straws connected near opposite ends, with the rings 11 and 12; while the straws of the other series are connected only at the upper portion thereof, that is, with ring 12. 60

In order to secure the proper position of the straws of the series connected at both ends, I provide partial relative rotation, of one ring 11 or 12, with reference to the other, 65 and in meantime the straws of the other series may be in their original position, that is, depending, without attachment of the lower ends or near the lower ends.

Assuming that the straws of the series 70 fully connected are then in proper inclined position, those straws connected only at their upper ends are moved to the position desired and are separately secured, by tying, or attaching to ring 11, near the bottom. It will 75 be observed therefore that all of the straws of one series are positioned at one time, and then the straws of the other series are positioned independently and individually and are then secured. 80

The cover comprises a plurality of straws 15 which are secured to ring 12 at such points as will permit straws 15 to project downwardly and outwardly, and the upper ends of straws 15 are secured to metallic ring or 85 other form of ring, shown at 16.

A particular form of joint for effecting connection is shown in Figure 2, and the end of the straw is provided with a V-shaped slot 18 adapted to be connected with ring 90 the ends of the fork in the straw projecting on opposite sides of the ring. A needle 19 now draws a thread 20 thru the forked end or prongs, and provides for the completion of the joint. 95

Connected with ring 16 are elements such as straws 22 which extend to a ring such as 23, and the latter is suspended by means of other similar elements 24 adapted for connection with ring 25. This provides for a 100 flexible type of connection, and for the suspension from a suitable point of a cord or string such as 26 by means of which the annular or other form of element 27 may be hung or mounted. This device last named 105 may be in the form of a swing in which the artificial bird 28 is positioned. It is not however, necessary that the device be regarded as of purely ornamental character, as a cage for practical use may be built up in 110 a similar manner, suitable provision of course being made for an entrance opening,

or for the temporary detachment of one or more elements of the wall or top.

It is intended that the device shall serve in part an educational or amusement purpose, and that the elements may be prepared and sold in knock-down form to be prepared and assembled by the purchaser or whoever may undertake to proceed with construction, along the lines indicated.

Having described the invention what is claimed is:—

1. In a device of the class described, a body portion constituting an open work structure of approximately circular form, a bottom for the body portion, and a top therefor, said top including a ring and members extending outwardly from the ring and over the edge of the body, these members being forked at their inner ends for cooperation 20 with the ring, and being secured to the ring

and body, and means for suspending the body and top from said ring.

2. The method of forming a cage like structure, which consists in connecting the upper ends of spaced elements in pairs with a frame member, and in connecting the lower end of one member of each pair with a second and lower frame member, producing relative rotatable movement between the frames, to carry the elements secured at both ends thereof to a position at an acute angle with reference to each frame, and then moving individually, in the opposite direction, those elements secured at only one end and connecting these elements with the lower frame at angles corresponding with the angles first named.

In testimony whereof I affix my signature.

ARTHUR RAYMOND DAVIAU, M. D.
